UNITED STATES PATENT OFFICE.

JAMES W. HOLLIDAY, OF LIBERTY, SOUTH CAROLINA, ASSIGNOR TO DRAPER COMPANY, OF HOPEDALE, MASSACHUSETTS, A CORPORATION OF MAINE.

FILLING-SEVERING DEVICE FOR LOOMS.

1,092,263.

Specification of Letters Patent. Patented Apr. 7, 1914.

Application filed April 30, 1913. Serial No. 764,480.

To all whom it may concern:

Be it known that I, JAMES W. HOLLIDAY, a citizen of the United States, and resident of Liberty, county of Pickens, State of South Carolina, have invented an Improvement in Filling-Severing Devices for Looms, of which the following description, in connection with the accompanying drawing, is a specification, like characters on the drawing 10 representing like parts.

This invention relates particularly to looms provided with automatic filling supplying mechanism, and has for its object the production of means for insuring the cutting 15 of the weft or filling thread at a predetermined point close to the selvage and between it and the point of attachment of the end of the filling. In looms provided with such filling severing devices it is important that 20 the end of the incoming filling should be severed as soon as possible, otherwise the filling may be broken and the end snapped into the fell and woven into the cloth causing a defect. Various devices have been designed 25 for securing a prompt severance of the filling and the object of this invention is to present a construction by which the desired result may be simply and accurately secured.

In this invention a filling catching device 30 is mounted on the lay and projects upwardly above the run of the incoming filling. This device is adapted to yield forwardly or toward the fell upon contact with said filling so that upon the backward movement of the 35 lay after replenishment the device yields and passes behind the filling and then on the succeeding beat-up carries the filling into the field of operation of the usual severing device.

40 The nature of the invention will appear more fully from the accompanying description and drawing and will be particularly pointed out in the claims.

The drawings illustrate only so much of 45 an automatic filling replenishing loom as is necessary to an understanding of the present invention.

In the drawings:—Figure 1 is a plan view showing a portion of the loom frame, lay, 50 filling feeder and filling severing means sufficient to illustrate in connection therewith the present invention. Fig. 2 is a front elevation showing a portion of the lay and shuttle box with the device of this invention

in place. Fig. 3 is a view partially in cross section of the construction shown in Fig. 2 enlarged and showing a preferred form of the filling catching device of this invention.

The loom frame, breast beam A⁴⁰, supplying mechanism, including the feeder to receive the filling carriers such as the bobbins supported from the hopper stand H, the weft or filling end holder b², the lay A³, the shuttle box S², the shuttle binder B, the temple T, and their associated parts are all 65 familiar and well known in automatic filling replenishing looms of this type, and need not be described in detail, not being specifically involved in this invention.

The filling severing means is mounted in 70 a fixed position adjacent the fell and selvage, and as shown for example in the patent to Lussier, 1,012,875 granted December 26, 1911, is commonly mounted on the temple. In the drawings, the cutting blade is shown 75 at C with its projecting ends c' and c². When the filling is beneath the ends c' and c² it is within the field of operation of the severing means and will be severed thereby. This invention is not concerned, however, 80 with the particular form of the severing means.

When a fresh filling carrier has been inserted in the shuttle by the operation of the automatic filling changing mechanism, and 85 the shuttle thrown across the lay A³, the end of the filling t will lead from the selvage of the cloth to the filling end holder b² as shown in full line in Fig. 1, and as the lay beats forward toward the breast-beam this 90 filling end is intended to be caught and severed by the severing means, but owing to variation in the character of fabric woven, the force required to beat the filling into the fell, the extent of the "bump of the cloth", 95 the position of the temple and other causes, the severing means frequently fails to sever the filling promptly.

This invention provides a filling catching device constituted as a finger mounted on 100 the lay, and projecting upwardly above the run of the incoming filling t and this finger is adapted to yield forwardly or toward the breast beam or fell upon contact with the run of filling. Upon the backward movement of the lay after replenishment this finger yields as the filling comes against it, the filling rides over it and the finger returns to 105

its upright position this time in the rear of the run of filling so that on the succeeding beat-up the finger carries the filling well forward and insures its passing into the field of the operation of the severing device.

In the specific form of construction illustrated as a preferred embodiment of the invention a bearing plate 10 is secured as by screws 11 to the front face of the lay and carries at its upper end about level with the raceway alined bearings 12 in which is mounted a shaft or pin 13. The filling catching device or finger is formed of thin metal and is indicated at 14. At its lower end this finger is split vertically, one section being bent to form a bearing sleeve 15 surrounding the shaft or pin 13, while the other section 16 depends below the shaft and constitutes a stop abutting against the plate 10 and limiting the rearward movement of the finger so as to maintain it in a substantially vertical position. The body of the finger 14 is curved slightly transversely so as to present a slightly convex surface against the filling at the rear of the finger. A spring 17 surrounds the shaft 13 and abuts at one end against the plate 10 and at the other end against the finger 14 thus serving normally to maintain the finger upright. This spring is delicate so that the finger readily yields as the filling comes against it and passes beneath the filling.

It will thus be seen that the invention by a very simple construction insures the filling on the second pick after replenishment being brought into the field of the severing device. In the drawings the dotted line position indicates the position to which the filling will be carried by the filling catching device upon the second beat-up after replenishment.

Having fully described my invention,

what I claim as new and desire to secure by Letters Patent is:

1. In a loom provided with automatic filling supplying mechanism, the lay, a severing device for the end of a fresh supply of filling mounted adjacent the selvage, a filling catching device mounted on the lay and projecting upwardly above the run of the incoming filling and adapted to yield forwardly or toward the fell upon contact with said filling, whereby upon the backward movement of the lay after replenishment the said device yields and passes behind the filling and on the succeeding beat-up insures the filling being carried into the field of operation of the severing device.

2. In a loom provided with automatic filling supplying mechanism, the lay, a severing device for the end of a fresh supply of filling mounted in fixed position adjacent the selvage, a finger pivotally mounted on the lay between said mechanism and said severing device, a stop to limit the rearward movement of said finger on its pivot and maintain it in vertical position, a spring normally holding the finger against said stop but permitting it to yield forwardly upon contact with the filling, whereby upon the backward movement of the lay after replenishment the said device yields and passes behind the filling and on the succeeding beat-up insures the filling being carried into the field of operation of the severing device.

In testimony whereof I have signed my name to this specification, in the presence of two subscribing witnesses.

JAMES W. HOLLIDAY.
